PEN-SHAPED POCKET FLASHLIGHT

Filed Jan. 21, 1950

UNITED STATES PATENT OFFICE

2,570,838

PEN-SHAPED POCKET FLASHLIGHT

Jerome Nathan and Richard W. Adler, New York,
N. Y., assignors to Bantam-Lite, Inc., New York,
N. Y., a corporation of New York

Application January 21, 1950, Serial No. 139,882

3 Claims. (Cl. 240—10.68)

1

This invention relates to flashlight construction, and more particularly is directed to a so-called pen or pencil-shaped flashlight, such as carried when not in use, in the pocket or handbag.

Among the objects of the invention is to generally improve flashlight constructions of the character described which shall comprise few and simple parts, which are readily assembled of easily manufactured parts, which shall be relatively cheap to produce in quantity production yet neat and attractive in appearance, which shall form a reliable and dependable pocket-size lighting means capable of withstanding rough and hard usage, which shall be convenient to handle and operate, and which shall be efficient and practical to a high degree in use.

Other objects of this invention will in part be obvious and in part hereinafter pointed out.

The invention accordingly consists in the features of construction, combination of elements, arrangement of parts which will be exemplified in the construction hereinafter described and of which the scope of application will be indicated in the claims following.

In the accompanying drawing in which one illustrative embodiment of the invention is shown.

Fig. 1 is a front elevational view of a so-called pen-shaped pocket flashlight construction embodying the invention.

Fig. 2 is a top plane or head end view of the improved flashlight construction shown in Fig. 1.

Fig. 3 is an enlarged cross-sectional view taken on line 3—3 in Fig. 1 showing the interior construction of the improved flashlight, with the switch thereof in an off-circuit position.

Fig. 4 is a greatly enlarged detailed cross-sectional view taken on line 4—4 in Fig. 3, and showing the switch in an on-circuit position in dot and dash lines.

Fig. 5 is an enlarged fragmentary elevational view of the head end cap of the improved flashlight construction shown in Fig. 1, partly broken away to expose the switch ring assembly structure.

Fig. 6 is a front elevational view of the extreme head end cap member with the extension portion thereof and the camming ring disassembled therefrom, the current carrying flexible jumper being shown secured in a normal off-circuit position, and the peripheral flange unbent before assembly shown in full lines and bent into assembly position in dot and dash lines, and

Fig. 7 is a top plan view of the camming ring for finger operation of the flashlight switch removed from the assembly.

2

Referring in detail to the drawing, 10 denotes a so-called pen pocket flashlight constructed to embody the invention such as carried in a pocket or handbag ready for use from a releasably mounted position like conventional pens or pencils by means of a suitable clamping attachment clip 11 in the well understood manner.

Said flashlight 10 may comprise a suitable outer battery casing 12, and as here shown being formed of a one-piece tubular metal having a closed end 12a for housing a standard electric battery, such as two series arranged dry cells 13 and 14, each cell being insulated from the casing 12 by a paper or fibre wrapper 15.

15 Open end 12b of casing 12 opposite said closed end 12a through which dry cells 13 and 14 are inserted and normally has carbon center contact 13a of cell 13 extending beyond said open end 12b which may be provided with a suitable

20 coupling means, such as spun or drawn screw threads 12c extending inward from said open end 12b, forming a seat and anchorage for a head end cap 16. The latter may carry a standard miniature incandescent lamp 17 extending

25 therethrough with bulb 17a thereof exposed to project light beams through top central opening 16a of head end cap 16, and base 17b of lamp 17 extending in axial alignment with battery cell 13, said lamp base 17b being retained by an insulating annulus 20 mounted in an extension end 16b of head end cap 16 so that center contact 17c of the lamp 17 is positioned to connect in circuit with battery carbon center contact 13a as shown in Fig. 3.

30 Said flashlight head end cap 16 may be made of spun or drawn sheet metal and when formed as a multi-part structure for economy of manufacture here shown, has a dome shaped portion 16c which is provided with said central opening 16a therein and which is interconnected with said extension end 16b. The latter forms a collar portion having spun or drawn screw threads 16d extending to provide with said casing screw

35 threads 12c companion coupling means, as is clear from Figs. 3 and 5.

40 For interconnecting dome portion 16c and extension collar 16b there may be provided an integrally formed inturned peripheral shoulder 16e spaced from an outturned locking peripherally extending edge flange 16f of dome portion 16c, extension collar 16b also having an inturned peripheral extending shoulder 16g for mating peripheral edge portion 16h thereof with an intermediate portion 16j of dome portion 16c extending

45

50

55

between said shoulder 16e and flange 16f to provide a rigid lap joint as said interconnection.

As seen from Figs. 3 and 4, the outer surface of extension collar edge portion 16h extending between said dome shoulder 16e and collar shoulder 16g of said assembled lap joint interconnection provides a circular sunken slideway in which a finger turning camming ring 18a rides for operating flashlight switch 18. Inner surface 16k of collar portion 16b between said flange 16f and threaded portion 16d, adjacent said lap joint interconnection firmly secures insulating annulus 20, in the assembly, dome collar outturned flange 16f serving as an abutment seat for said annulus 20. The thickness of the latter may be made such as to extend said annulus 20 to just short of rim edge of casing open end 12b so that center contact 17c of lamp base 17b projecting therebeyond for contacting in the assembly with said battery cell contact 13a, as shown in Fig. 3.

Inner peripheral side 20a of insulating annulus 20 may be provided with uniformly spaced apart ledges 20b to form frictional engaging supporting means for outer surface 17d of lamp base 17a which, as shown in Figs. 3 and 4, serves as a base screw shell contact for the lamp 17 in the well understood manner.

As is clear from Figs. 3, 4 and 6 said edge portion 16h of extension collar 16b and underlying intermediate portion 16i of dome 16c may be partially cut away or slotted in registered alignment as denoted generally at 16m to accommodate free movement of elongated current carrying flexible spring jumper 18b which may be anchored in position at one end thereof by rivet 18c. The other portion or free end 18d of said jumper 18b is positioned to swing beyond said slot 16m, said free end 18d being flexed from a normal "off"-circuit position to "on"-circuit position, shown in Fig. 4, in full and dot and dash lines, respectively, in the manner hereinafter described and provide a rubbing, that is, a self cleaning contact with the aligning lamp base outer surface 17d.

Switch camming ring 18a which may be mounted for limited rotation in said sunken slideway as described above and shown in Figs. 1 to 5, has the outer peripheral surface 18e ribbed or knurled part way therearound to provide finger gripping means, the remaining part 18f, which in the assembly rotates between the clip 11 and dome portion 16c may be imprinted to carry "on" and "off" circuit marking 18g.

Extending inwardly from inner circular surface 18h of camming ring 18a and into slot 16m there may be provided a projection or protuberance 18j carried or formed integrally with said ring 18a which on the rotation thereof along a path of the length of said slot 16m from a position just beyond jumper free end 18d, as shown in full lines in Fig. 4, leaving the jumper 18b in a normally off-circuit position, to a position flexing said jumper 18b with projection 18j bearing thereagainst to force said end 18d thereof to close the circuit at outer lamp base surface 17d in "on"-circuit position as shown in dot and dash lines in Fig. 4. A releasable locking nub 18k may be provided on a midportion of jumper 18b for engaging with said projection 18j to retain said switch 18 in on-circuit position against accidental displacement.

The practical operation of the invention will now be apparent. With head end cap 16 positioned in the complete assembly as described

above and shown in the drawing, and with a suitable helical pressure spring 19 mounted in the casing closing end 12a bearing on zinc terminal 14a of dry cell 14 as shown in Fig. 3, the lamp 17 is retained in proper assembled position by lamp base 17b in frictional secured engagement with insulating annulus ledges 20a. Now, finger manipulating switch 18 by turning switch camming ring 18a fully in a counterclockwise direction as shown in Figs. 1 to 4, projection 18j thereof extending through slot 16m is moved beyond jumper free end 18d and said jumper 18a springs into a normal "off" circuit position with said jumper end 18d spaced from lamp base 17b, as shown in full lines in Fig. 4.

To switch the jumper 18a into an effective "on" circuit position, the camming ring 18a is finger manipulated for rotating as far as it can be readily turned clockwise to a position corresponding to that indicated in dot and dash lines moved

in Fig. 4, preferably until projection 18j is moved passed nub 18k.

During said latter rotation jumper 18a, is subjected to camming action by projection 18j for flexing free end 18d thereof to and away from making a wiping contact on lamp base surface 17d. Should the switch camming ring 18a be turned a less distance than is necessary to obtain a stabilized position to retain the circuit closed, jumper 18a, adjacent the free end thereof, may be made effective by providing a sloping surface as at 18m, to give switch 18 a tendency to force the latter in "off" circuit position as is clear from Fig. 4.

To "open" circuit switch 18 after the latter has been "closed" camming ring 18a is simply rotated counterclockwise to the position first described.

Clip 11 may be of a U-shaped cross section formed with a clamping free end 11a and a suitable anchored end 11b opposite said free end 11a, said anchored end 11b being firmly fastened to dome portion 16c. Said clip 11 is so designed, arranged and positioned as not to interfere with the finger manipulation of switch camming ring 18a, and also permits ready ascertaining the switch position through observance of said marking 18g with relation to clip 11.

It should be noted that flashlight 10 is not only constructed of very simple parts, but also lends itself to form a neat and attractive personal article ready and convenient for use.

It will thus be seen that there is provided an improved pocket flashlight construction in which the several objects of the invention are achieved and which are well adapted to meet the conditions of practical use.

As various possible embodiments of the invention may be made in the above invention and as various changes may be made in the embodiment above set forth, it is to be understood that all matters herein set forth and shown in the accompanying drawing are to be interpreted as illustrative and not in a limiting sense.

Having thus described our invention we claim as new and desire to secure by Letters Patent:

1. In a flashlight head end cap construction, a metallic dome portion interconnected to a metallic collar extension having means for mounting on an open end of a battery casing, said dome portion having an inturned shouldered midsection and an outturned edge flange, said collar extension having a rim edge portion fitted to extend between said dome shouldered midsection and said flange, an inturned shoulder provided on a

midportion of said collar extension positioned to extend over said flange for firmly interlocking said dome portion to said collar extension at the interconnection therebetween and to form a sunken slideway for a finger manipulating switching ring to ride in, said slideway having an elongated slot wherethrough electrical circuit switch means extend on rotation by said ring, the portion of said collar extension between said mounting means and said inturned shoulder serving as a seat for a insulating lamp base supporting means.

2. In a flashlight construction having a metallic tubular casing formed with a top opening for housing a dry cell battery, a metallic head end cap formed with an extension collar fitting portion for demountably securing on said casing open end, said cap having an elongated slot extending through said fitting portion, an incandescent lamp positioned within said cap with a base of said lamp aligning with said slot, a spring current conducting jumper having one end swingably secured from a rim end of said slot, a free end of said jumper being bent to slope toward said lamp base, an insulating annulus secured within said cap beyond a path of swinging movement of said jumper for removably retaining the lamp base in a desired alignment, a switching ring encircling said cap mounted for rotation thereon and provided with an integral protuberance extending into said slot for flexing said jumper to electrically contact the said free end thereof against the lamp base on rotation of said ring from an "off" to an "on" switching position, said cap and fitting portion formed with a sunken slideway in which the encircling ring rides and wherein said elongated slot lies, a clip anchored to said cap over the path of movement of said rotation, and finger gripping means formed as a portion of a peripheral side of said ring with another portion of said peripheral ring side positioned to travel under said clip on rotation of said ring for limiting said movement of ring rotation to said "off" and "on" switching positions.

3. In a flashlight construction, a metallic tubular battery casing formed with top open and closed bottom ends, a metallic head end closure cap mounted on said casing open end having an elongated peripherally extending slot adjacent said casing open end, an incandescent lamp extending through said cap with a base of said lamp aligning with said slot, a spring current conducting jumper having one end secured to a rim end of said slot, a free end of said jumper being bent to slope toward said lamp base, an insulating annulus retained by said cap inwardly of said slot for mounting the lamp base in alignment with a battery cell terminal housed in said casing, a switch ring encircling said cap mounted for limited rotation to extend over said slot and jumper, and a camming projection carried by said ring to extend into said slot for flexing said jumper free end to electrically contact said lamp base on rotation of said ring from an "off" to an "on" circuit switching position, a clip anchored to said cap to extend over the switch ring, and finger gripping means formed on portion of a peripheral side of said ring, another portion of said peripheral ring side extending to travel under the clip on the rotation of the ring being provided with marking indicating said "off" and "on" circuit switching positions.
